UNITED STATES PATENT OFFICE.

ALFONS R. WEICH, OF NEWARK, NEW JERSEY.

TOY.

1,237,846.

Specification of Letters Patent. Patented Aug. 21, 1917.

Application filed September 8, 1916. Serial No. 118,954.

To all whom it may concern:

Be it known that I, ALFONS R. WEICH, a citizen of the United States, residing in the city of Newark, in the county of Essex and State of New Jersey, have invented certain new and useful Improvements in Toys, of which the following is a full, clear, and exact description, such as will enable others skilled in the art to which it pertains to make and use the same, reference being had to the accompanying drawings, and to numerals of reference marked thereon, forming a part of this specification.

My invention relates to improvements in toys of the class in which a return ball is used, the object being to provide an improved toy consisting of an apertured board and a ball-throwing device which can be inexpensively produced and which is simple in construction and operation.

A further object of my invention is the production of a toy, by means of which a number of games may be played, such as the game of pinless ten pins, or table baseball or the like, by using the apertured board in the one case as a "pin-board" and in the other case as "field-boards."

My present invention therefore consists in the novel construction of a toy embodying the principles hereinabove mentioned, and of a character to be more fully described in the following specification. This invention consists furthermore in the several novel arrangements and combinations of the various parts, as well as in the details of construction of the same, all of which will be hereinafter more fully set forth and then finally embodied in the clauses of the claim which are appended to this specification.

The invention is fully illustrated in the accompanying drawings, in which—

Figure 1 represents a side elevation of my improved device, the same being illustrated as mounted upon a board.

Fig. 2 represents a front elevation of the apertured board, which as convenience may require, may be a "pin-board" or a "field-board;" and

Figs. 3, 4 and 5 represent respectively, a plan view, a side elevation, and a front elevation of the ball throwing device.

Similar numerals of reference are employed in all of the above described views, to indicate corresponding parts.

Referring now to the said drawings, the complete device consists essentially of a ball

throwing device 1, and an apertured board 2, which as the case may be, may be utilized as a "pin-board" or a "field-board" or the like. These parts may be conveniently mounted upon any desired form of base-board, not shown, or they may be set up on a table, a floor or the like, at a convenient distance apart to suit the desires of the players.

The apertured board, which as a whole, is designated by the reference character 2, in its preferred form, consists of a piece of cardboard 3 provided with a plurality of apertures 4. Two opposite edges of the cardboard are provided with pins or pivots 5, by means of which it is pivotally supported between the standards, which may be of any desired or convenient form, each preferably consisting of a suitable base 7, from which rises a post 8, apertured near its top for the reception of the pin or pivot 5.

My preferred form of ball throwing device, as illustrated in the drawings, consists of a base 9, from which rises a standard 10, to one side of which, near the top thereof, is pivotally secured a ball support 11. The ball support 11 is provided with an elongated slot 12, through which projects the free end of a pivoted lever 13, which slot 12 forms a guide for the pivoted lever, the other end of said lever being hingedly connected to the base by means of a support 14, in any convenient or desired manner. This ball support 11 is pivotally secured to the standard 10 so as to permit the discharge end of the support to be moved either up or down, thereby enabling the player to direct the ball to the different heights of the apertures 4 as he may desire. Projecting from the forward end of said support 14 is a dowel 15, which dowel is removable from said support, thereby enabling the ball throwing device to be more readily and conveniently packed in a box or the like.

To the forward end of the dowel 15, one end of a spiral spring 16 is secured; the other end of said spring being secured to the pivoted lever 13 in any convenient or desired manner. Attached to the forward end of the dowel 15 is a cord 17, to the other end of which is secured the rubber ball 18. The top of the forward end of the pivoted ball support 11 is grooved, as at 19, to receive said rubber ball 18.

The ball support 11, adjacent to the elongated

gated slot 12, and near the forward end thereof, and at the rear end of the groove 19, is provided with two wire nails 20 or the like, against which nails the ball 18 rests and is positioned, when the pivoted lever 13, by means of the tape 21 is retracted against the tension of the spiral spring 16, preparatory to striking the ball 18. The rearward movement of the pivoted lever 13 is limited by the end of the elongated slot 12 in the pivoted ball support 11, thereby preventing too great an expansion of the spring and its subsequent fracture.

This being the construction of my novel toy, the manner of using or manipulating will be readily apparent, and it will be noted that if the ball is placed in the groove upon the ball support, and the free end of the pivoted lever is pulled back into the position illustrated in Fig. 1 of the drawings, the ball will roll into its proper position in the groove 19 against the two nails 20, and if then the pivoted lever is suddenly released, the same will drive the ball and cause it to be projected through the air toward the apertured board 2, and if said ball passes through any of said apertures, it will be retained therein until it is desired to withdraw the ball therefrom by means of the string, the manipulation requiring skill and proving very interesting and amusing.

The apertured board, as illustrated in the drawings, if the game of pinless ten pins is to be played, is provided with ten apertures, each aperture being numbered, and one thereof marked "Strike". The "pin-board" is set up at a desired distance from the ball throwing device, and the ball is placed upon the ball support. The spring or lever is then pulled back, permitting the ball to roll in its proper position, and thereafter, the spring or lever is suddenly released, sending the ball toward the apertured board.

Experience has demonstrated that the organization above described, is a highly efficient and amusing one, and while I have shown the preferred form of my invention, I do not wish to be limited to the exact details of construction shown and described, as obvious modifications thereof, not involving the exercise of invention, may be made by any skilled mechanic, and such departures from what is herein described and claimed I consider within the scope and terms of my claims.

I claim:

1. In a device of the class described, a ball throwing device comprising a flat base, a standard mounted on said base, a support secured in close proximity to said standard, a hinged member carried by said support, a dowel extending from the forward side of said support, a spring connecting said hinged member and said dowel, a ball sup-

port and a tape secured to the free end of said hinged member to retract said spring to propel a ball.

2. In a device of the class described, a ball throwing device comprising a flat base, a standard mounted on said base, a support secured in close proximity to said standard, a hinged member carried by said support, a dowel extending from the forward side of said support, a spring connecting said hinged member and said dowel, a pivoted ball support extending from one side of said standard, said ball support having a slot extending rearwardly from the pivot, and a groove extending forwardly from the pivot, and means located on the top of said ball support for positioning a ball and a tape secured to the free end of said hinged member to retract said spring to propel a ball.

3. In a device of the class described, a ball throwing device comprising a base, a standard mounted on said base, a supporting member mounted on said base in close proximity to said standard, a hinged member carried by said support, a dowel extending from the forward side of said support, a spring connecting said hinged member and said dowel, a pivotally adjustable ball support extending from one side of said standard, said ball support having a slot extending rearwardly from the pivot, in which the hinged member moves, and a groove extending forwardly from the pivot, in which a ball rides, and means located on the top of said ball support and in juxtaposition with the groove for positioning a ball and a tape secured to the free end of said hinged member to retract said spring to propel a ball toward the target.

4. In a device of the class described, a ball throwing device comprising a base, a standard mounted on said base, a spring-actuated hinged member carried by said base, and a ball support provided with an elongated slot, extending from one side of said standard, and through which the free end of said spring-actuated hinged member extends, whereupon upon retraction and release of said spring-actuated hinged member a ball is propelled.

5. In a device of the class described, a ball throwing device comprising a base, a standard mounted on said base, a spring-actuated hinged member carried by said base, a pivoted ball support extending from one side of said standard, said ball support having a slot extending rearwardly from the pivot, in which the spring-actuated hinged member moves, and a groove extending forwardly from the pivot and means located on the top of said ball support for positioning a ball, whereby upon retraction and release of said spring-actuated member a ball is propelled.

6. In a device of the class described, a ball throwing device comprising a base, a standard mounted on said base, a spring-actuated hinged member carried by said base, a pivotally adjustable ball support extending from one side of said standard, said ball support having a slot extending rearwardly from the pivot, in which the spring-actuated hinged member moves, and a groove 10 extending forwardly from the pivot, in which a ball rides, and means located on

the top of said ball support and in juxtaposition with the groove for positioning a ball, whereby upon retraction and release of said spring-actuated hinged member a ball is 15 propelled.

This specification signed and witnessed this 2nd day of September, 1916.

ALFONS R. WEICH.
